DESIGN FOR A CLOCK OR SIMILAR ARTICLE

Arthur A. Wofinsohn, Chicago, Ill.

Application June 14, 1940, Serial No. 93,007

Term of patent 3½ years

To all whom it may concern:

Be it known that I, Arthur A. Wofinsohn, a citizen of the United States, residing at Chicago, in the county of Cook and State of Illinois, have invented a new, original, and ornamental Design for a Clock or Similar Article, of which the following is a specification, reference being had to the accompanying drawing, forming a part thereof.

Figure 1 is a top plan view of a clock or similar article showing my new design; and

Figure 2 is a front elevational view of Figure 1.

The essential features of my design for a clock reside in the specific configuration of the hull and other parts and the placement of these parts in a manner as shown.

I claim:

The ornamental design for a clock or similar article, substantially as shown and described.

ARTHUR A. WOLFINSOHN.
